ORWELL H. NEEDHAM, OF NEW YORK, N. Y.

Letters Patent No. 101,152, dated March 22, 1870.

IMPROVEMENT IN TREADLES.

The Schedule referred to in these Letters Patent and making part of the same

To all whom it may concern:

Be it known that I, ORWELL H. NEEDHAM, of the city, county, and State of New York, have invented a new and useful Improvement in Treadle-Motions, of which the following is a full, clear, and exact description, reference being had to the accompanying drawings forming part of this specification, and in which—

Figure 1 represents a front view of a treadle-motion, with my improvement applied thereto;

Figure 2, a sectional view of the same, taken at right angles to fig. 1, as indicated by the dotted line $x\ x$; and

Figure 3, a transverse section through the rock-shaft of the treadle, at the line $y\ y$, in fig. 1.

Figures 4 and 5 represent views at right angles to each other, in illustration of a modified construction of the means by which power is communicated through the foot to start the crank-shaft, when the same stops with the crank on the dead-center, and to insure its being started in a forward direction at all times.

Similar letters of reference indicate corresponding parts.

My invention is applicable to treadle motions generally, irrespective of the purpose to which the same are designed to be applied, but is more particularly intended for connection with the treadle motions of sewing-machines.

The invention consists in a shoe arranged over the treadle-shaft, with freedom to turn thereon or around, and made to operate, through a pawl, on a ratchet-wheel secured to the crank-shaft, for starting the latter when stopping on its dead-center, also for insuring its forward movement on starting after stopping, whatever the position of the crank, by which arrangement every facility is afforded to the operator, who works the treadle, for setting in motion said starting device or mechanism, and the same is free from interference with or by the rock-shaft of the treadle.

Also, the invention includes an extension of said shoe over the treadle, so that, in applying the foot or feet to work the latter, the shoe which operates the starting mechanism is depressed or automatically applied, as it were, to actuate the starter, and is held down during the working of the treadle without interfering with the application of the foot or feet to the treadle.

Referring, in the first instance, to figures 1, 2, and 3 of the accompanying drawing—

A represents the rock-shaft of the treadle, and B, the treadle thereon.

C is the crank-shaft;

D, the crank; and

E, the pitman, which connects the treadle with the crank.

Arranged in a free or loose manner, as regards its fulcrum, a , on or over the rock-shaft A, as the center of motion, is a lever, carrying at its free end, or made to form a shoe, F, which it is preferred to extend over the treadle B, so that, in applying the foot to the latter, said shoe will come under the arch of the foot and in no way interfere with the application of the foot to the treadle, while by such arrangement the starter of the crank-shaft, of which said shoe forms a part, is automatically applied, as it were, by the act of applying the foot or feet to the treadle.

The devices used in connection with the shoe F to start the crank-shaft C over its center, or to insure to it a forward movement whatever the position of the crank, consist of a pawl or dog, G, pivoted to a lever-box, H, which is arranged loose on the crank-shaft, and which is connected, by a rod, I, with the lever-shoe, said pawl biting into or gearing with a ratchet-wheel, J, fast on the crank-shaft, and being held in suitable position to actuate the crank-shaft, or returned to its requisite position therefor after operation by a spring, K, which may either be of rubber or metal, and which is arranged to draw on the lever-box H till arrested by a stop, L, applied to the lever-shoe F; or said spring and stop may be otherwise arranged to produce a like action or effect, and, in some cases, the lever-shoe may be of different order, that is, the fulcrum may be at one end, the weight or rod I at the other end, and the power to operate it applied in between.

It is not necessary, in fact, that the shoe F should be of lever-form, inasmuch as a slotted shoe or slide, F', arranged to embrace the rock-shaft A, and lying over the treadle B with the rod I attached to it, may be used instead, as represented in figs. 4 and 5 of the drawing.

What is here claimed, and desired to be secured by Letters Patent, is—

1. The arrangement of the shoe F or F' over the rock-shaft A of the treadle, and so that it is capable of oscillating upon said rock-shaft, in combination with the pawl G, operated by said shoe and ratchet-wheel J on the crank-shaft C, through connecting-rod I, substantially as specified.

2. The arrangement of the shoe F or F' over or relatively to the treadle B and its rock-shaft A, essentially as specified, and for the purpose herein set forth.

Witnesses: ORWELL H. NEEDHAM,
FRED. HAYNES,
R. E. RABEAU.
